UNITED STATES PATENT OFFICE.

GEORGE F. BARD, OF NORWICH, CONNECTICUT.

IMPROVEMENT IN COMPRESSION STOPS AND WASTES.

Specification forming part of Letters Patent No. 155,633, dated October 6, 1874; application filed June 17, 1874.

To all whom it may concern:

Be it known that I, GEORGE F. BARD, of Norwich, in the county of New London and State of Connecticut, have invented a Compression Stop and Waste, of which the following is a specification:

The figure is a longitudinal section of the device, in which B and C are the two induction and eduction passages; b and d, the two rubber-cushioned valves; "a," the slotted stem; f, the outlet for waste; a, the spindle to operate the device.

When the upper valve is closed, (and it always is when the lower one is open,) the water cannot get into the upper chamber. It therefore cannot run out of the waste, as said waste is in the upper chamber.

When the lower valve is closed, if you keep turning the spindle, the upper valve will open and let the back water into the upper chamber and out of the waste. Both valves open and shut with the water.

The stem, rotated by the hand, is slotted and hollow, and receives into it the winged end of the main stem e.

A coil-spring insures the prompt raising of the valve d.

I am aware that double valves are used and compression waste-cocks, and I therefore only lay claim to my peculiar arrangement of the same.

I do not lay claim to any of the devices shown in patent of H. A. Chapin, August 21, 1860, No. 29,744.

I claim—

The combination of the slotted stem, the screw-stem provided with wings and with a valve opening with the water, and the lower valve and the two seats, all as and for the purposes set forth.

GEORGE F. BARD.
